Primary Examiner — S. Bryan Reinholdt, Jr.*Assistant Examiner* — James T Tyree(74) *Attorney, Agent, or Firm* — Perry Hoffman(57) **CLAIM**

The ornamental design for a toy projectile launcher apparatus, as shown and described.

DESCRIPTION

FIG. 1 is a front perspective view of the toy projectile launcher apparatus according to our present design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan elevational view thereof.

The broken lines shown and unshaded areas adjacent to them are included for the purpose of illustrating the unclaimed portions of the article and form no part of the claimed design.
